Primary Examiner — Cathy A MacCormac(74) *Attorney, Agent, or Firm* — Martino Patent Law at the Law Offices of Sepehr Daghighian(57) **CLAIM**

The ornamental design for a combined triple knotted braided rope and ball pet toy, as shown and described.

DESCRIPTION

FIG. 1 is a perspective view of a combined triple knotted braided rope and ball pet toy embodying my new design; FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view of embodiment of FIG. 1;

FIG. 9 is a front elevation view of FIG. 8;

FIG. 10 is a rear elevation view of FIG. 8;

FIG. 11 is a right side elevation view of FIG. 8;

FIG. 12 is a left side elevation view of FIG. 8

FIG. 13 is a top plan view of FIG. 8; and,

FIG. 14 is a bottom plan view of FIG. 8.

The broken lines depict environmental subject matter, are for illustration only and form no part of the claimed design.
